AUTOMATIC CHUCKING MACHINE

Arthur J. Lewis, Stratford, Conn., assignor to The
Baird Machine Company, Bridgeport, Conn., a
corporation of Connecticut

Application January 26, 1933, Serial No. 653,641

34 Claims. (Cl. 29—38)

This invention relates to automatic chucking machines in which a plurality of tools operate simultaneously and successively upon a corresponding number of pieces of work.

More particularly, the present invention is concerned with improvements in chucking machines of the type in which a rotary turret carrying a circular series of rotary work holders indexes relatively to a tool carriage to present the pieces of work successively to a series of tools carried by the tool carriage and simultaneously actuated by cams into and out of cooperative relation with the corresponding pieces of work during the dwell periods of the turret, certain of the tools being arranged longitudinally of the work while other tools are arranged transversely of the work.

In accordance with the present invention a vertical automatic chucking machine is provided which is distinctive in that the center column carrying the rotary turret and longitudinal tool slides is flanked by a pair of opposite vertical columns, each having two transverse slides on opposite sides for appropriate tools which are reciprocated into and out of cooperative relation with pieces of work located at the four corresponding tooling stations, and this movement of the transverse tool slides takes place concurrently with a reciprocating movement of the longitudinal tool slides to bring the tools thereof into and out of cooperative relation with the same pieces of work.

Another feature of the invention is the mechanism whereby the longitudinal and transverse tool slides are reciprocated. The transverse tool slides mounted on each vertical side column are reciprocated by individual cams mounted on a continuously rotating shaft arranged within the corresponding side column and these vertical side shafts, through intermittent driving gears, oscillate a rotary cam drum having individual cams for reciprocating the longitudinal tool slides, each of the cams for the transverse and longitudinal tool slides being constructed to cause the corresponding tools to perform movements commensurate with the particular tooling operations required of them.

The invention also includes as a feature a common mechanism which performs the dual function of opening the work holders or chucks presented successively to the loading station for unloading and reloading, and of connecting the work holder or chuck spindles located at the tooling stations to the driving mechanism at the end of each indexing movement of the work-holding turret and disconnecting these spindles from the driving mechanism to permit the turret to index.

This mechanism includes a single cam at the top of the machine which reciprocates a rod extending through the center column of the machine and connected to the devices for engaging and actuating the opening mechanism of the chucks located at the loading station and also to clutching devices arranged to couple the chucks located at the tooling stations to the driving mechanism. The movement of this rod in one direction by the cam at the beginning of the dwell period of the turret effects the opening of the chucks at the loading station and the coupling of the chucks at the tooling stations to the driving mechanism, and the opposite movement of the rod at the end of these dwell periods of the turret effects the disconnection of the chuck-opening devices and chuck-driving mechanism to permit the turret to index to present successive chucks to the loading and tooling stations and to the corresponding chuck-opening and driving devices.

The driving mechanism of the work holder or chuck spindles located at the tooling stations is also one of the features of the invention and includes a drive shaft extending through the center column of the machine, driven by variable speed driving gearing at the top of the machine and connected at its lower end through individual adjustable speed gear trains to the corresponding coupling devices of the chucks located at tooling stations. With this arrangement, the speed of rotation of all of the chucks as well as the speed of rotation of the individual chucks may be varied at will to be commensurate with the tooling operations to be performed on the pieces of work carried by the chucks.

A further feature of the invention is the mechanism whereby the work-holding turret is indexed to present the pieces of work carried in the chucks thereof successively to the tooling stations. This mechanism includes an indexing disc mounted on one of the vertical side shafts and having pawls which periodically engage turret abutments so arranged that the shock of engagement thereby of the pawls is reduced and the massive turret is gradually brought up to rapid indexing speed and as gradually brought to rest upon completion of the indexing movement, despite the inertia and momentum of the turret. Simply by changing the number of indexing pawls and the cam of a corresponding turret locking device, the machine may be converted from single-indexing to double-indexing and vice versa.

Other features of the invention include safety mechanism automatically operative to stop the

machine in response to improper loading of the work in the chucks, failure of the operator to remove finished work, and delayed operation of the chuck loading and unloading devices; means for 5 backing up or reversing the rotation of the turret for recutting a piece of work, removing a defective piece of work, test cutting, and the like; the spillway arrangement of the tool lubricant trough causing the lubricant to flush the chips 10 from the operating part of the machine; and other novel arrangements described in connection with the accompanying drawings, in which

Figure 1 is a front elevation of the automatic chucking machine of this invention;

15 Figure 2 is a vertical section through the machine;

Figure 3 is a plan view of the driving mechanism at the top of the machine as seen along the line 3—3 of Figure 2;

20 Figure 4 is a vertical section through the driving mechanism as seen along line 4—4 of Figure 3;

25 Figure 5 is a transverse section through the base of the machine as seen along the line 5—5 of Figure 2 and illustrates the arrangement of the driving gear train of the individual chuck spindles and the chuck opening mechanism at the loading station;

30 Figure 6 is an enlarged vertical section through the chuck opening mechanism at the loading station;

35 Figure 7 is a transverse section through the machine as seen along the line 7—7 of Figure 2, and illustrates the arrangement and relationship of the longitudinal and transverse tool slides;

Figure 8 is an enlarged vertical section of the turret indexing and locking mechanism;

40 Figure 9 is a transverse section through the upper end of the center column as seen along the line 9—9 of Figure 2, and illustrates the structure of the oscillating cam drum for the longitudinal tool slides and the work locators;

45 Figure 10 is a vertical section through one of the transverse tool slides and the actuating mechanism therefor, as seen along the line 10—10 of Figure 7;

50 Figure 11 is an enlarged vertical section through the left-hand side column as seen along the line 11—11 of Figure 7, and illustrates the cams and other mechanism for reciprocating the transverse tool slides;

55 Figure 12 is a transverse section through the longitudinal tool slide oscillating drive mechanism, as seen along the line 12—12 of Figure 2 and illustrates the condition of the mechanism when the longitudinal tool slides lie in retracted position;

60 Figure 13 illustrates the condition of the mechanism when the longitudinal tool slides lie in advanced position;

Figure 14 is a perspective view of the control mechanism of the machine;

65 Figure 15 is an enlarged cross section through the detent disc of the safety stop mechanism of the control mechanism as seen along the line 15—15 of Figure 16;

70 Figures 16 and 17 illustrate two conditions of the safety stop mechanism of the control mechanism, the former showing the stopping of the machine in the event that the work is not properly seated in the chucks, and the latter the stopping of the machine in the event that the operator fails to act at the proper time to unload and reload the chucks at the loading station; and

75 Figure 18 is a vertical section through the chip

disposal trough, as seen along the line 18—18 of Figure 1.

Referring to Figure 2 of these drawings, numeral 20 designates the base of the machine on which is supported the central column 21 and the apron 22, which supports side columns 23 and 24, which in turn support the driving mechanism housing 25 having a cover plate 26.

The driving mechanism

Located within housing 25 at the top of the machine is the main driving mechanism, which is driven by an electric motor 27 supported on the top of the driving mechanism housing 25 and adjustable thereon in accordance with standard practice by means of adjusting screws 28. A plurality of belts 29 pass over the sheave 30 of the motor 27 and a sheave 31 secured on the end of horizontal cross shaft 32 suitably journaled on the base 42 in the driving mechanism housing 25, as shown particularly in Figures 3 and 4. Keyed on cross shaft 32 is a bevel gear 33 which drives bevel gear 34 secured on horizontal shaft 35. A high speed clutch 37 is mounted on the shaft 35, one element of which is connected to spur gear 36 and the other element of which is connected to the collar 38 slidable on shaft 35 and is engaged by yoke 39 mounted on shifter rod 40, the axial movement of which effects the engagement and disengagement of clutch 37. Movement of rod 40 to the left, as seen in Figure 3, engages the clutch 37, and movement of rod 40 to the right effects the disengagement of clutch 37. Shifter rod 40 is engaged by one end of a bell crank 41 pivoted on the base 42 of the driving mechanism and having a roller 43 at its other end, which is adapted to engage successive cams 44 and 45 mounted on cam disc 46 carrying worm wheel 47 and secured on the upper end of shaft 48 extending through right-hand column 24 and journaled at 49 and 50 in the housing 25 and right-hand column 24, respectively.

The spur gear 36 is connected to the driven element of clutch 37, and meshes with a spur gear 52 secured to the driven element of main clutch 53 mounted on shaft 54. Secured on spur gear 52 is a ratchet wheel 55, the teeth of which are normally engaged by a spring-pressed pawl 56 slidable in the hub 57 of worm wheel 58 journaled on shaft 54. Worm wheel 58 is driven from main drive shaft 35 by means of a speed-reducing train of gears which includes meshing skew gears 59 and 60, spur pinion 61 connected to skew gear 60 and meshing with spur gear 62, having a spur pinion 63 meshing with spur gear 64, carrying the worm which drives worm wheel 58 at reduced speed. When main clutch 53 is engaged and high speed clutch 37 is disengaged, worm wheel 58 drives shaft 54 at low speed. When high speed clutch 37 is engaged, worm wheel 58 continues to rotate because it is directly driven from main drive shaft 35, but in that case ratchet wheel 55 is not driven by pawl 56 but over-runs it, since it is driven at higher speed, the pawl 56 clicking idly over the teeth of ratchet wheel 55. The high speed drive of shaft 54 is effected through high speed clutch 37, spur gears 36 and 52, clutch 53 and shaft 54.

Clutch 53 is the control clutch for the machine through which the high speed and low speed drives take place, but a second clutch 65 is provided on shaft 54 for effecting the reverse drive thereof independently of clutch 53, the latter being disengaged when reverse clutch 65 is engaged. Both clutches 53 and 65 are controlled

5 by a collar 66 splined on shaft 54. When the collar 66 is in its left-hand position, as seen in Figure 4, to engage clutch 53, clutch 65 is disengaged, and when collar 66 is moved to its right-hand position, as seen in Figure 4, reverse clutch 65 is engaged and the main clutch 53 is disengaged. The driving portion of clutch 65 is connected to spur gear 67 which, through reversing idler gear 69 is driven continuously by pinion 69
10 secured on main drive shaft 35. Clutch collar 66 is connected by yoke 70 to shifter rod 71 pivoted on the end of crank 72 mounted on horizontal shaft 73 journaled in housing 25 and projecting from opposite sides thereof, as is illustrated in Figures 3 and 14. Connected to the projecting end of shaft 73 at the front of the machine is a lever 74 having a horizontal handle bar 75 at its free end, the other end of which is carried by a lever 76 suitably journaled at its opposite 15 end on a pin 77 in the housing 25. A handle bar 78, similar to handle 75 is located at the rear of the machine and is also connected to shaft 73 so that the main clutch 53 and reverse clutch 65 may be operated from either the front or the rear 20 of the machine. Thus, by moving handle 75 or 78 to the right, as seen in Figures 3 and 14, main clutch 53 is engaged to drive the mechanism at either high or low speed, depending upon whether or not cams 44 and 45 hold clutch 37 in engaged 25 or disengaged position, and, by moving handle 75 to the left, main clutch 53 is disengaged and reverse clutch 65 is engaged to reverse the rotation of shaft 54 and the parts of the machine driven thereby.

30 The right-hand end of shaft 54 carries the worm 79 which meshes with and drives right-hand worm wheel 47 mounted on the cam disc 46 of the vertical cam shaft 48 in right-hand side column 24. The opposite or left-hand end of shaft 54 is fitted with worm 80, of opposite pitch to that of worm 79, which meshes with worm wheel 81 secured on cam disc 82 keyed on vertical cam shaft 83 extending through left-hand side column 23 and journaled at its upper end in bearing 84 of housing 25 and at its lower end in bearings 85 and 86 in base 20. When the machine is running in the normal forward direction, right-hand cam shaft 48 rotates in a counter-clockwise direction and left-hand cam shaft 83 rotates in a clockwise direction.

The turret

55 Journalled on bushings 87 on central column 21 and supported on a rail 88 on base 20 is the work-holding turret 89.

60 Mounted on the turret is a circular series of rotary work-holding chucks 90 of conventional design and arranged to rigidly hold a piece of work while the tooling operations are performed 65 thereon. These chucks 90 are each mounted on a vertical spindle 91 journaled in bearings 92 and 93. The lower end of each spindle 91 is fitted with one element 94 of a crown jaw clutch, the other element 95 of which is mounted on the upper end of the vertical drive shaft 96 journaled in bearings 97 in the base 20 and axially slideable with these bearings. Each spindle drive shaft 96 is urged toward clutch-engaging position by a coil spring 96'. Accordingly, when shaft 96 is moved downwardly its clutch element 95 disengages spindle clutch element 94, and when shaft 96 is released, its spring 96' moves it upwardly to engage clutch 94-95. Except for the 70 two chucks 90, which are positioned at any one

time at the front of the machine or loading station, a spindle drive shaft 96 is provided for each of the chucks 90. Thus, as in the particular machine illustrated, if there are eight chucks, there are six spindle drive shafts 96, so that during each 10 tooling period six of the eight chucks are driven while two of them, that is, the two located at the loading station at the front of the machine, are not driven but remain stationary for removal and replacement of work.

15 As shown in Figures 2 and 5, each spindle drive shaft 96 is fitted with a spur gear 98 meshing with a pinion 99 secured on a stub shaft 103, suitably journaled on base 20 and carrying spur gear 101, which meshes with spur gear 102 secured on the lower end of hollow shaft 103 extending upwardly through center column 21 and journaled therein in bearings 104. The upper end of shaft 103 projects into driving mechanism housing 25 and carries the bevel gear 105 which 20 is driven by bevel pinion 106 mounted on horizontal stub shaft 107 journaled in base 42 of the driving mechanism. The other end of stub shaft 107 carries spur gear 108 which meshes with spur pinion 109 keyed on jack shaft 110 having 25 splined thereon a series of spur gears 111 of different diameters, which are shiftable along shaft 110 so as to mesh with corresponding gears 112 mounted on drive shaft 32 and connectible thereto by means of clutch 113. Simply by shifting 30 the splined gears 111 along shaft 110 to change the driving relationship between them and gears 112, the speed of rotation of all of the work-holding chucks 90 may be conveniently varied.

35 The release collar 114 of chuck spindle clutch 113 is connected by yoke 115 to shifter rod 116, which is controlled by cam 117 and 117' of right-hand cam disc 46 through bell crank 118 pivoted on the base 42 of the driving mechanism. The action of cam 117 is synchronized with the 40 ret-indexing mechanism to be described, and operates to disengage clutch 113, so as to stop rotation of the chucks 90 immediately prior to each indexing movement of the turret to facilitate disengagement of their clutches 94-95, and cam 45 117' acts to again restore the rotation of chucks 90 for the tooling operations immediately after each indexing movement of the turret is completed.

50 Not only may the speed of rotation of all of the work-holding chucks 90 be adjusted at will by shifting gears 111 in the manner described, but the speed of rotation of individual chucks with respect to the other chucks may be varied to suit particular tooling requirements. Thus, for 55 one tooling operation it may be desirable or necessary to rotate the work at a higher speed, such as for fine cutting, than is necessary when a rough cutting tooling operation is required. To this end, spur gears 98 and 99 are replaceable by 60 gears of different diameters, so that one chuck spindle may have gearing providing a different speed ratio than other chucks, as is indicated in Figure 5 by the varying diameters of the driving gears of certain of the chuck spindles. These 65 gears are readily accessible for changing through openings on the base 20 covered by removable cover plates 119 at the front and rear of the machine, as indicated in Figure 1, while speed change gears 111 in the driving mechanism housing 25 70 75 are also readily accessible by lifting the cover plate 26.

The drive of the chuck spindles 91 is effected from shaft 32 through clutch 113, one of the gears 112 meshed with the corresponding gear 75

111, jack shaft 110, spur gears 109 and 108, shaft 107, bevel pinion 106, bevel gear 105, vertical column shaft 103, spur gears 102, 99 and 98, drive shaft 96 of each chuck spindle except those located at the loading station, engaged clutch 94—95 and the chuck spindle of corresponding chuck 90.

10 Each of the drive shafts 96 of the chuck spindles 91 is supported at its lower end in a yoke 129 pivoted intermediate the ends of a lever 121, which is in turn pivoted at one end on a horizontal pin 122 secured on the base 20, as illustrated in Figures 2 and 5. The free end 123 of each of the levers 121 engages the upper disc 125 of the 15 spool formed by spaced discs 124 and 125 mounted on the lower end of a rod 126 slideable through hollow vertical shaft 103 in the center column 21 of the machine.

20 The upper end of rod 126 is fitted with the block 127, which is engaged by one end 128 of lever 129 pivoted on a bracket 130 of driving mechanism base 42 and provided at its other end with a roller 131 which follows the contour of crown cam 132 mounted on left-hand cam disc 82, 25 as illustrated in Figure 2. Crown cam 132 is synchronized with the turret indexing mechanism to be described, so that just prior to each indexing movement of turret 89, cam 132 lowers rod 126 to move chuck spindle drive shaft levers 30 121 downwardly against the tension of springs 96' to disengage jaw clutches 94 and 95 and permit the indexing of the turret. Immediately upon completion of each indexing movement of the turret, cam 132 raises rod 126 so as to allow 35 springs 96' to engage each of the chuck spindle clutches 94 and 95 and permit the restoration of the rotation of the chucks 90 by cam 117 in a manner previously described. During the vertical movement of each of the clutch shafts 96, 40 as effected by cam 132, the teeth of the gears 98 thereof slide through the teeth of meshing pinions 99 with a splining action.

45 Located in alignment with the two chuck spindles 91 which are located at the loading station 45 at the front of the machine is a pair of push pins 133, each of which is seated in a tubular rod 134 slideable through a bushing 135 in the base 20 and adjustably threaded at its lower end in clevis 136, which is pivoted on the lever 137. This lever 50 is pivoted at one end on pin 138 of frame 20 and is connected at its other end 139 to the spool formed by discs 124 and 125, as illustrated especially in Figure 6. Push pin 133 is secured in rod 134 by means of a shear pin 140, and rod 55 134 is locked in adjusted position on clevis 136 by lock nut 141. The shear pin 140 is a safety arrangement, preventing injury to the chuck or work in case the chuck jams closed for any reason.

60 The push rod 133 is adapted to be elevated into engagement with the lower end of chuck-opening rod 142 which extends upwardly through the spindle 91 of each chuck and opens the chuck when it is advanced by elevation of the end 139 65 of lever 137. Chucks of this nature have been standardized and need not be further described.

65 Axial movement of rod 126 by cam 132 not only effects the engagement and disengagement of chuck spindle clutches 94 and 95 but also 70 currently effects the opening of the two chucks located at the loading station. Since cam 132 also controls the operation of the chuck opening pins 133, these pins become effective to open the chucks immediately after each indexing operation and are withdrawn out of the way pre-

75 paratory to each indexing operation, holding the corresponding chucks open during dwell periods of the turret for removal and replacement of work.

80 It will be observed that both the chucks at the tooling stations and the chucks at the loading stations are substantially simultaneously controlled by cam 132, which, through lever 129, rod 126 and spool 124—125, actuates levers 123 of the spindle rotating mechanism of the chucks 10 located at the tooling stations and, through levers 137 and pins 133, actuates the chuck-opening mechanism for the chucks located at the loading station.

The turret indexing mechanism

15

Upon completion of each tooling operation the turret is advanced a step, carrying the pieces of work to the next tooling position for the succeeding operation and, in order to decrease the 20 non-working period of the machine, the indexing takes place at relatively high speed, being effected at the time that the high speed clutch 37 of the driving mechanism of the machine is in engagement, i. e., after cam 44 has engaged 25 clutch 37 and before cam 45 disengages this clutch for slow operation of the machine. When high speed clutch 37 is engaged, ratchet wheel 55 is driven at a higher speed than worm wheel 58 carrying the pawls 56, so that the ratchet 30 wheel 55 over-runs worm wheel 58 and drives shaft 54 at high speed, so that the respective right-hand and left-hand vertical cam shafts 48 and 83 are also driven at high speed.

35 Secured on left-hand vertical shaft 83, adjacent the lower edge of turret 89, is a disc 143 carrying a plurality of spaced roller pawls 144 on its upper surface (Figs. 2, 7 and 8), the number of these roller pawls 144 determining whether the turret is single- or double-indexing. If 40 there are two roller pawls, the turret is single indexing, being moved during each indexing operation through an angle equal to the angle between adjacent tooling stations or adjacent chuck spindle drive shafts 96. If four roller pawls 144 45 are employed, as is indicated in Figure 7, the turret is double-indexing, that is, it moves through an angle during each indexing operation which is equal to twice the angle between adjacent tooling stations. Two and four roller pawl 50 discs 143 are interchangeable on shaft 83. Projecting in the path of the roller pawls 144 and located on the lower edge of turret 89 is a circular series of spaced abutments or lugs 145, alternate ones of which are of different shape. Certain 55 of these abutments diverge outwardly and others converge outwardly, the diverging and converging abutments being spaced alternately as indicated in Figure 7, the converging abutments being designated 145 and the diverging abutments 60 145'. Diverging abutments 145' are adapted to be engaged by the leading pawl roller 144 at the beginning of the indexing operation, and the diverging side wall thereof causes the corresponding pawl roller 144 to gradually and easily engage it so that the shock of engagement between these parts is minimized and the beginning of the indexing movement of the turret is retarded slightly to effect this result. Conversely, the trailing pawl roller 144 engages one of the converging abutments 145, so that the release thereof by the trailing pawl roller is retarded and the shock of sudden stopping of the movement of the turret at the end of the indexing operation is also minimized. With this arrangement the 75

heavy and massive turret is advanced intermittently with the easy and shockless movement of a much lighter and smaller mass.

As before mentioned, during the complete indexing movement, cam 44 holds high speed clutch 37 in engagement so that the indexing or non-working movement of the machine does not greatly detract from the total working period of the machine. Also, the contours of the cams 44 and 45 are proportioned with respect to the number of pawl rollers 144 so that the high speed movement of the turret begins at the proper time and terminates at the end of the indexing movement. Furthermore, the movements of cam 132 which controls the opening and closing of the chucks located at the loading station, as well as the drive of the chucks located at the tooling stations, are correlated to conform to the indexing movements of the turret, so that chuck spindle clutches 94-95 are disengaged just prior to the indexing movement and reengaged immediately thereafter, while chuck-opening pins 133 are actuated to open the corresponding chucks immediately after the completion of each indexing movement and are withdrawn out of the way immediately before the next indexing movement begins.

The turret 89 is locked against movement during the periods between its indexing movements or dwell periods, by a pin 146 adapted to engage one of the notches formed in blocks 147 spaced around the periphery of turret 89. The locking pin 146 is slidably mounted in a block 148 secured to the base 20 of the machine, as illustrated in Figures 7 and 8. The pin 146 is normally urged inwardly by a spring 149 so as to engage in the notch of a corresponding block 147 to hold the turret rigidly during tooling operations. Engaging pin 146 is the end of a lever 150, which is journaled on a pin 151 in base 20, and which carries at its free end the cam-following roller 152 arranged to engage ring cam 153 mounted on left-hand vertical cam shaft 83. The contour of the ring cam 153 is such that, just prior to each indexing operation of the turret 89, it actuates lever 150 to withdraw pin 146 from the notch in a corresponding block 147, so as to release the turret 89 for indexing. At the completion of each indexing movement, cam 153 releases pin 146, so that its spring 149 urges it into the notch of a corresponding turret block 147. When the double-indexing disc 143 is employed, as illustrated in Figure 7, the contour of cam 153 is such that pin 146 skips alternate blocks 147 to permit the double-indexing operation. For single-indexing the cam 153 is shaped so as to release pin 146 for engagement in the notches of successive blocks 147.

It will be observed that the drive of the chuck spindles 91 is wholly independent of the high-speed and low-speed turret indexing mechanism, except that the rotation of the chuck spindles is synchronized with the movements of the turret so that chuck spindles 91 are stationary and disconnected from their drives during the indexing movements of the turret and rotate during the dwell periods of the turret.

The vertical or longitudinal tool slides

Corresponding to each of the chucks 90, except the two which are located at the loading station at any one time, is a plurality of tool slides 155, which are slidably vertically on blocks 156 secured to the vertical flat faces of center column 21, as illustrated especially in Figures 2 and

7. Secured to the surfaces of tool slides 155 are the tool holders 157, each bearing the appropriate tool for performing the predetermined tooling operation on the work carried by the chucks 90, which are aligned with the several tools and which move step-by-step relatively to them during the indexing movements of the turret 89 to present successive pieces of work to the several tools so that the latter may perform their particular operations thereon.

As illustrated in Figure 2, each of the vertical tool slides 155 is supported on a vertical block 158. Each tool slide 155 and its corresponding block 158 are adjustable vertically or longitudinally with respect to each other by a screw 159 passing through a lug 160 on the slide 155 and threaded into the block 158. The unbalanced weight of each tool slide 155 is compensated for by a coil tension spring 161 suitably connected to the corresponding slide 155 at one end and at its other end to a lug 162, which is mounted on the upper end of block 156 on column 21, as shown in Figure 2.

The upper ends of each of the six tool slides 155, of the particular form of machine illustrated, carries a roller 163 which engages a corresponding individual segmental cam 164 mounted on the cam drum 165, as shown in Figures 2 and 9. The cam drum 165 is mounted for oscillatory movement about a vertical axis on a bushing 166 secured on the upper end of center column 21. The weight of the cam drum 165 is supported by a roller thrust bearing 167 mounted on center column 21 and the cam drum 165 is centered against upward displacement by a thrust bearing 168 interposed between its upper surface and the lower surface of base 42 of the driving mechanism within housing 25. It will be observed that the cam drum 165 takes its bearing on center column bushing 166, and that tool slides 155 are also supported on center column 21, so that the tools and their actuating cams 164 are firmly supported on the rigid center column 21 and are not susceptible to vibration or displacement due to any resistance offered by the work to the tools or strains set up in the mechanism as a result of any unusual work which it may be called upon to do.

The individual segmental cams 164 of the corresponding longitudinal tool slides 155 are shaped so that, upon oscillation of the cam drum 165, the tools carried by the tool slides are reciprocated vertically, the speed of the tools in opposite directions being determined by the rate of angular movement of the cam drum 165 in opposite directions as it oscillates.

The oscillation of cam drum 165 is effected by mechanism illustrated in Figures 2, 12 and 13. As shown in these drawings, cam drum 165 is fitted with diametrically opposite gear segments 169 and 170, each adapted to be periodically engaged by respective mutilated gears 171 and 172 mounted on constantly rotating cam discs 46 and 82, respectively, of right-hand and left-hand vertical cam shafts 48 and 83, respectively.

As right-hand mutilated gear 171 rotates continuously in a counter-clockwise direction, the teeth 173 thereof engage the toothed segment 169 of cam drum 165 to rotate the latter in a clockwise direction through the appropriate angle, determined by the number of teeth 173 and 169, which is sufficient to advance or lower the tool slides 155 the appropriate distance to cause the tools carried thereby to effect their tooling operations on the pieces of work aligned therewith.

in the then bodily stationary but axially rotating chucks 90. The movement of cam drum 165 in a clockwise direction from the position illustrated in Figure 12 to the position indicated in Figure 13 is limited by a set screw 174 threaded through a lug 175 in housing 25.

The vertical tools are retracted from the work by mutilated gear 172, the teeth 177 of which engage cam drum gear segment 170 as indicated in Figure 13 to rotate cam drum 165 through a predetermined angle in a counter-clockwise direction, this angle being such as to raise tool slides 155 a sufficient distance for retracting the tools from the work preparatory to the next indexing movement of the work-holding turret 89. A set screw 178 threaded through lug 179 on gear housing 25 serves to limit the return movement of cam drum 165 and performs the same function as set screw 174.

One of the end teeth 180 of cam drum gear segment 169 is made longer than the other teeth and engages the toothless edge of mutilated gear 171 during the dwell period of cam drum 165 prior to the time that left-hand mutilated gear 172 comes into action. Thus, cam drum 165 is locked in stationary position by the engagement of elongated tooth 180 with the edge of mutilated gear 171, which, however, is recessed at 181 to permit long tooth 180 to pass during periods of relative movement between cam drum 165 and mutilated gear 171, which are not effected by the latter but by mutilated gear 172. A similar elongated tooth 182 on left-hand gear segment 170 of cam drum 165 cooperates with the toothless rim of mutilated gear 172 to perform this same locking function, the rim of gear 172 being recessed at 183 to provide clearness between mutilated gear 172 and elongated tooth 182 during relative movement between them, which is not effected by them but by mutilated gear 171.

After the retracting or elevating movement of the tools by cooperation between left-hand mutilated gear 172 and cam drum 165, there is a dwell period during which the tool slides 155 remain stationary in retracted or elevated position to permit the turret 89 to index. The intermittent gearing illustrated in Figures 12 and 13, by which the vertical or longitudinal tool slide cam drum 165 is oscillated, are synchronized with the movements of the turret, that is, the angular relationship of turret-indexing pawl rollers 144, the turret locking cam 153 and the intermittent cam drum oscillating gearing is such as to secure the properly timed sequence of operations of the corresponding parts in the manner described.

It is during the low-speed drive of the main driving mechanism illustrated in Figures 3 and 4 that the tooling operations take place. In order to effect this low speed, drive cam 45 actuates bell crank 41 to cause shifter rod 40 to disengage high-speed clutch 37 which remains disengaged during the dwell period of the turret, that is, until cam 44 re-engages it at the beginning of the high-speed indexing movement of the turret 89. The low-speed drive of the vertical slide cam shafts 48 and 83, which carry the mutilated gears 171 and 172, respectively, is effected from main drive shaft 35 through skew gears 59 and 60, spur gear train 61, 62, 63 and 64, worm wheel 58, pawls and ratchet 55—56, engaged main clutch 53, shaft 54, and worms 79 and 80 which drive respective worm wheels 47 and 81 carrying cam discs 46 and 82, respectively, on which the mutilated gears 171 and 172 are respectively mounted.

The cross or horizontal tool slides

As illustrated in Figure 7, each of the vertical side columns 23 and 24 carries two horizontal tool slides, one on each lateral surface. The front and rear tool slides 185 and 186, respectively, 5 are slidably mounted on guides 187 and 188 secured on the front and rear surfaces of right-hand side column 24, carry respective tool holders 189 and 190 on their outer surfaces. These tool holders are provided with the appropriate tools 10 for performing the tooling operations on the work held in the two corresponding chucks, which are located in proper radial position with respect thereto at any one time during the dwell periods 15 of the turret 89. The tools may be such as to perform facing, or cross-cutting, or cross-drilling, boring or reaming operations on the work, for example, or any other tooling operation which the nature of the work may require. The front and rear horizontal tool slides 191 and 192, respectively, 20 are guided in the same way on the front and rear surfaces of left-hand side column 22.

The particular arrangement of these slides is 25 illustrated in Fig. 10, which is a cross section through left-hand rear tool slide 192 as seen along the line 10—10 of Figure 7, showing the slide on the stationary column guide 193, a stationary bearing 194 passing therethrough, and a longitudinal rack 195 carried by the tool slide 192. Meshing with this rack 195 is a pinion 196 secured on the outer end of a shaft 197 journaled in stationary column bearing 194 and carrying on its inner end the pinion 198. The arrangement of pinion 198 is also illustrated in Figure 11, which 30 is an enlarged vertical section through left-hand column 23 as seen along the line 11—11 of Figure 7. The tool slide 192 is adjustable horizontally or longitudinally of its rack 195 by means of screw 199, so that the position of the tool carried by 35 slide 192 may be adjusted relatively to the work, and the slide may be adjusted relatively to the starting and finishing positions of the corresponding rack 195. Each of the other tool slides 185, 186 and 191 is similarly arranged and, therefore, 40 the description of tool slide 192 will suffice for all of them.

As shown especially in Figure 11, the pinion 198 at the inner end of pinion shaft 197 meshes 45 with a vertical rack 200 slidable in suitable guides 201 in left-hand column 23. One of such racks 200 is provided for each of the four cross or horizontal tool slides and they are all alike, each meshing with a pinion corresponding to pinion 198 in Figure 11. The upper end of each rack 200 carries a cam roller 202 which engages in the groove of a corresponding crown cam 203 secured on left-hand vertical cam shaft 83. This cam shaft carries a similar crown cam 204 which actuates the rack 191 of front left-hand tool slide 191. The right-hand vertical cam shaft 48 carries two similar crown cams, the upper one of which, designated 205, actuating the rear right-hand horizontal tool slide 86 through rack 206, shown in Figure 7, and the lower crown cam 209 on right-hand drive shaft 48 actuating front right-hand horizontal tool slide 185 by means of rack 209, shown in Figure 7.

The movements of these cross or horizontal 70 tool slides are synchronized with the indexing of the turret, so that they are projected forward to engage the work held in the corresponding chucks during the dwell periods of the turret 89 and are withdrawn therefrom just prior to the 75

next indexing movement of the turret. These cross or horizontal tool slides are also arranged so that these tools cooperate on the corresponding pieces of work concurrently with the tools carried by the longitudinal or vertical tool slides.

The control mechanism

In addition to the front and rear handle bars 75 and 78, respectively, whereby the starting, 10 stopping and the reversing of the machine may be manually controlled, there is a treadle 210 at the loading station of the machine, as is illustrated in Figures 1, 5 and 14. This treadle 210 is pivoted at its ends in lugs 211 on the base 20 15 of the machine, and is normally urged into elevated position by a coil spring 212 connected at one end to the treadle 210 and anchored at its other end on the base 20 at the front of the machine, as is illustrated in Figure 1.

20 Pivoted on the treadle 210 so as to be drawn downwardly when the treadle is depressed, is a vertical rod 213, pivoted at its upper end on the free end of a lever 214 secured on the right-hand end of a shaft 215 extending across the front of 25 the machine and journaled in brackets 216 secured to the center column 21 of the machine, this arrangement being shown particularly in Figure 14. Secured on shaft 215 is a pair of spaced levers 217 and 218. Depending from the 30 free ends of these levers are respective rods 219 and 220, the lower ends of which are connected to levers 221 and 222, respectively, which are pivoted intermediate their ends on brackets 223 and 224, respectively, secured on the center column 21 above the two chucks 90 located at the loading station at the front of the machine. The free ends of levers 221 and 222 are connected by a pin and slot combination to corresponding work locators 225 and 226, slidable vertically in 35 brackets 223 and 224, and aligned or substantially aligned with the two chucks 90 located below them at the loading station of the machine.

As illustrated in Figures 1 and 14, one of these work locators, namely, the left-hand one, 225, is 40 provided with a gauge 227 adapted to engage the work placed in the corresponding chuck 90 in such a way that before work can be removed from this chuck the gauge 227 must be withdrawn. A similar gauge may be mounted on the 45 right-hand work locator 226, or a centering ring, not shown, or any other arrangement cooperating with the particular piece of work which is to be toolled in the machine. It will be seen that as treadle 210 is depressed, work locators 225 and 226 are elevated, and that when no pressure is applied to treadle 210 spring 212 normally urges it upwardly so that the work locators 225 and 226 are urged downwardly.

Pivoted intermediate the ends of lever 214 is a 50 vertical link 228, having an eye 229 at its upper end through which a normally horizontal rod 230 is slidable. This rod 230 is adjustably mounted in the end of a bar 231, pivoted at its other end to the free end of a crank 232 secured on a shaft 55 233 journaled through the wall of driving mechanism housing 25 and extending into this housing, as is shown especially in Figure 3. Secured on the inner end of shaft 233 and within driving mechanism housing 25 is a lever 234 having a roller 235 at its free end, which engages the profile of inverted crown cam 236 secured on cam disc 46 of right-hand vertical cam shaft 48, as is illustrated in Figures 2 and 3. Rod 230 with bar 60 231 is accordingly suspended between the eye

229 of vertical link 228 and the free end of crank 232.

Pivoted on a pin 237 in bar 231 is a disc 238, which is held in any angular position, limited by stop 239, by a spring 240 on pin 237, as is illustrated in Figure 15. Also pivoted on pin 237 and frictionally engaging the rear surface of disc 238, so as to move therewith, is a plunger 241. The disc 238 is provided with two substantially opposite detents 242 and 243 adapted to respectively 10 engage the upper and right side edges of abutment 244 secured to the front surface of driving mechanism housing 25.

As previously mentioned, before the operator can remove a piece of finished work from one of 15 the chucks located at the loading station and replace it with a new piece of work, he must withdraw work locators 225 and 226 which prevent access to these pieces of work when they are located in their normal downward position. The 20 operator withdraws these work locators by depressing treadle 210 and then may remove the finished work from the stationary open chucks at the loading station and reload the chucks with new pieces of work. He then releases the treadle 25 210 and the work locators 225 and 226 descend to engage the work in the reloaded chucks. If the chucks are properly reloaded, link 228 holds pin 230 and plunger 241 above a lug 245 on arm 246 of stop handle 75, so that the subsequent feeling 30 action of cam 236 causes the pin 230 and plunger 241 to move over the lug 245 without engaging it. However, if one of the pieces of work is not properly seated, so that work locators 225 and 226 cannot descend to the full distance, link 35 228 remains lowered to hold rod 230 down, so that the subsequent feeling action of cam 236 causes rod 230 to engage lug 245 and move lever 74 to the right to disengage main clutch 53 and stop the machine. The operator then places the 40 work in the chucks properly and starts the machine by moving handle 75 to the center position to reengage main clutch 53. This condition is illustrated in Figure 16. The same action takes place if the operator tends to hold treadle 210 45 depressed longer than the dwell period of the turret and in order to prevent indexing before the operator is ready, the safety mechanism stops the machine in the manner described.

If the machine completes a cycle and the operator fails to depress treadle 210 to remove the finished work, the feeling action of cam 236 projects rods 230 and plunger 241 over the lug 245, but detent 243 engages the right edge of abutment 244 to cause disc 238 to rotate in a counter-clockwise direction and drop the plunger on lug 245, so that on its return movement plunger 241 falls into alignment with lug 245. Accordingly, during the next feeding movement of cam 236 the plunger 241 actuates lever 74 to disengage 60 main clutch 53 and stop the machine to prevent retooling of the finished work and unnecessary movement of the machine. This condition of the machine is illustrated by Figure 17. Depression of the treadle then causes detent 242 to engage 65 the upper edge of abutment 244 and elevate plunger 241 to reset the safety mechanism.

When it is desired to run the machine continuously, the safety mechanism may be disabled by moving cam lever 246 to the right to raise plunger 70 241 out of range of the lug 245.

The projecting upper ends of work locators 225 and 226 are provided with rollers 247 and 248, respectively, which engage respective segmental cams 249 and 250 secured on cam drum 165, 75

which, it will be recalled, is oscillated by the mechanism illustrated in Figures 12 and 13 to actuate the vertical or longitudinal tool slides. These cam segments 249 and 250, shown in Figure 9, raise work locators 225 and 226 to withdraw and hold withdrawn from the work the gauges 227, or the like, during the indexing movement of the turret. Upon completion of each indexing movement of the turret, cams 249 and 250 again lower the work locators, so that they must be raised by the operation of the treadle 210 in order that the operator may gain access to the corresponding pieces of work.

Journalized within right-hand vertical drive shaft 48 is a vertical shaft 251 having at its upper end a bevel gear 252 which is driven by a bevel gear 253 secured on one end of a horizontal shaft 254 journaled on cover plate 246 and driven from drive shaft 32 by bevel gears 255 and 256. The lower end of vertical shaft 251 carries a spur gear 257 meshing with an idler gear 258, which in turn drives the pinion 259 of oil pump 260 mounted in a chamber 261 formed within the apron 22, as illustrated in Figure 2. This oil pump 260 provides forced-feed lubrication for the parts of the machine and is conveniently located and driven from the main driving mechanism in the manner described.

Formed by apron 22 and surrounding the turret 89 is a trough 262 having a slope toward the back of the machine and a discharge spout 263 whereby the tool lubricant sprayed on the tools during their periods of cooperation with the work is carried away. As shown particularly in Figure 2, the upper surface of the turret 89 is of relatively steep pitch and leads downwardly toward trough 262. The steepness of the slope causes the tool lubricant to flow downwardly into trough 262 with such velocity that it carries the tooling chips with it, while the pitch of the trough 262 is so steep that the chips are carried out through spout 263 by the tool lubricant and do not collect in the trough to clog it after a considerable period of operation of the machine. The pitch of the trough 262 and of the adjacent surfaces of the turret leading into the trough are steepest at the roughing stations on the right-hand side of the machine adjacent the discharge spout 263, as seen in Figure 2, so that the heavier and larger chips 50 are as readily flushed away as are the smaller and lighter chips discharged at the finishing stations on the left-hand side of the machine. Thus, mechanical devices for scraping chips through the trough 262 or other chip-removing means 55 become unnecessary.

As is illustrated in Figure 18, the joint between the turret 89 and the trough 262 is sealed by overlapping strips of metal, one of which, 264, is mounted on the edge of the turret 89 and is turned downwardly to overlap the upwardly turned strip 265 mounted on the edge of the trough 262. This forms a substantially liquid-proof joint, but in the event that liquid escapes therethrough because of splashing, it is collected in an auxiliary trough 266 located in the upper surface of base 28 below the overlapping metal sealing strips 264 and 265, as shown in Figure 18. This trough encircles the entire machine and is pitched downwardly toward spout 263 into which it discharges through passage 267, as shown in Figure 2.

A splash guard 268 is supported on the center column 21 and overhangs the upper edge of the turret 89, as shown in Figure 2. This splash

guard 268 prevents splashing of the tool lubricant into the bearings 87 of the turret 89.

Summary of operation

Preparatory to starting the machine into operation, the operator provides the vertical or longitudinal tool slides 155 with appropriate tools 157 and the horizontal tool slides 185, 186, 191 and 192 with the appropriate tools for performing the corresponding tooling operations on the work. In the type of machine illustrated in the drawings, there are six tooling or working stations and two loading or unloading stations. At each of the six tooling stations, the six vertical or longitudinal tools may operate on the corresponding pieces of work held in the chucks 90 below, while the tools carried by the horizontal slides operate on the work at the first, second, fifth and sixth tooling stations. The tools may perform practically any kind of work, such as turning, boring, reaming, recessing, chamfering, forming, longitudinal and cross drilling, threading, tapering, facing, etc.

If the machine is single indexing, that is, if the two-roller pawl indexing disc 143 is placed on right-hand vertical shaft 83, each piece of work held in each chuck is successively operated on by tools at each of the six working stations. When the machine is arranged for double indexing, that is, when the four-roller pawl indexing disc 143 is provided, as illustrated in Figure 7, two pieces of work are finished in each cycle or one piece of work having received two chucking operations is finished at each cycle. The cam 153, controlling locking pin 146 is appropriately shaped for single-indexing or double-indexing, being held withdrawn by the cam 153 while the turret moves through a single angle for single-indexing, or while the turret moves through a double angle for double-indexing. Also, before the machine is started the operator selects the appropriate gear combinations provided by gears 111 and 112 in the driving mechanism housing 25 (Fig. 3) in order to secure a slow or more rapid drive of all of the work-holding chucks, depending upon requirements. Also, depending upon the tooling requirements, the operator arranges the driving gears 98 and 99 of the individual chuck spindles to revolve the corresponding chucks at various rates of speed. Then the gauges 227 or other equivalent devices are adjusted on work locators 225 and 226 so that they engage the upper ends or other parts of the work when the latter is properly seated in the chucks at the loading station and the machine is ready for operation.

The two chucks at the loading station are open, since cam 132 through rod 126 holds push pin 133 in engagement with chuck-releasing rods 142, as illustrated in Figure 6. With the two chucks at the loading station open, the operator depresses treadle 210 to withdraw work locators 225 and 226 and their gauges 227, or the like, so that he may have access to the chucks for placing work in them.

After placing the work in the chucks the operator releases treadle 210 so that the work locators and gauges descend to engage the work to properly center or otherwise locate it in the chucks depending on the requirements. If the work is properly located as determined by the safety mechanism, the operator may move handle bar 75 or 78 to the right to engage the main driving clutch 53 to start the machine into operation. If the work has not been properly seated

in the chucks the work locators and gauges do not descend as far as is necessary to permit the machine to start; that is to say, the work locators detect the fact that the machine is not in proper operating condition. In that event, cam 236 advances rod 230 and plunger 241 to engage lug 245 of handle bar 75 and shift it to the left (Fig. 16) to stop the machine immediately after it has been started by the shifting of handle bar 75 to the right in the manner described.

Assuming that the work has been properly seated in the chucks and that the feeling action of cam 236 is ineffective because of that fact, the cam drum 165 is oscillated by the intermittent gearing illustrated in Figures 12 and 13, so that cam segments 249 and 250 carried thereby raise work locators 225 and 226 from the work to permit the turret 89 to index. The same rotation of cam drum 165, which also carries longitudinal or vertical tool slide actuating cams 164, elevates the corresponding vertical or longitudinal tool slide 155 to retract the tool holders 157 and their tools out of the path of the work carried in the chucks, so that the turret 89 may index. The same action takes place in regard to the horizontal or cross tool slides 185, 186, 191 and 192, the corresponding cams 205, 208, 203 and 204, on vertical drive shafts 48 and 83, acting to withdraw these tool slides out of the path of movement of the work carried by the chucks 90 to permit the turret to index.

Before the turret indexes, cam 153 mounted on left-hand vertical cam shaft 83 withdraws locking pin 146 from the notch in the corresponding turret block 147 in which it was located during the dwell period of the turret. Further rotation of left-hand vertical drive shaft 83 causes indexing disc 143 to insert one of its pawl rollers 144 beneath the lower surface of the turret 89 so as to engage the inwardly sloping surface of diverging abutment 145. The slope of the side of diverging turret abutment 145 results in the gradual and shockless cooperation between the corresponding pawl roller 143 and the heavy massive turret 89 which accordingly starts to move. The practical result of this is the same as though the turret were moved at one-half the speed, since the slope of the abutment 145 is opposite to the direction of movement of the turret. If the turret is single-indexing, the second pawl roller 144 on disc 143 engages the following converging turret abutment 145, and since the slope of this abutment is opposite to the slope of diverging abutment 145, the latter compensates for the effect on the movement of the turret produced by diverging abutment 145, but it also causes the turret to slow down just before it stops so as to reduce the shock effect of the momentum of the heavy turret. If the machine is double-indexing the four pawl rollers 144 operate in the same way except that they move the turret through a double angle instead of through a single angle. Before the turret begins to index, cam 44 on right-hand cam disc 46 engages high-speed clutch 37 (Figs. 3 and 4) which drives shaft 54 at a higher speed directly through spur gears 37 and 52, the ratchet wheel 55 over-running the more slowly moving worm wheel 58 during this high speed drive. At the end of the indexing movement of the turret cam 45 on right-hand cam disc 46 disengages high-speed clutch 37 so that the shaft 54 is again driven at slow speed through the pawl and ratchet wheel combination 55-56 connected to low-speed worm wheel 58 (Fig. 4). Also, at the end of the indexing move-

ment, cam 153 releases locking pin 146 so that it engages in the notch in corresponding turret block 147 to lock the turret securely against movement during the tooling operation.

During the time that the indexing movement of the turret is taking place, oscillating cam drum 165 remains stationary, holding all of the longitudinal or vertical tool slides retracted so that the tools are out of the path of movement of the work carried by the indexing turret, and also holding work locators 225 and 226 and their corresponding gauges disengaged from the work. As the indexing period is completed, left-hand mutilated gear 172 oscillates cam drum 165 in a counter-clockwise direction to the position illustrated in Figure 13. During this movement, the cam segments 164 carried by cam drum 165 advance the vertical or longitudinal tool slides 155 to bring the tools carried thereby into cooperative relation with the work carried by the corresponding chucks 90. Also, cams 205 and 208 on right-hand vertical drive shaft 48 advance the tools carried by corresponding transverse tool slides 185 and 186 into engagement with the corresponding pieces of work located at the first and second tooling stations. Simultaneously, cams 203 and 204 advance the tools carried by left-hand transverse tool slides 191 and 192 into cooperative relation with the pieces of work located at the fifth and sixth tooling stations. This movement of cam drum 165 is also accompanied by the lowering of work locators 225 and 226 and their gauges into engagement with the pieces of work in the chucks located at the loading stations, this action being performed by the segments 249 and 250 on cam drum 165.

Just prior to the cooperation between the several tools and the corresponding pieces of work, cam 132 raises rod 126 to release levers 121 so that the springs 96 engage the driving clutches 94 and 95 of each of the six chucks located at the working stations to set the pieces of work carried thereby into rotation before the corresponding tools engage them at the beginning of the tooling operation. When cam 132 raises rod 126 it also opens the two chucks located at the loading station by advancing their opening rods 142 by means of push pins 133 mounted on the levers 131 actuated by the spool 124-125 mounted on the lower end of rod 126. The chuck-driving mechanism including the vertical drive shafts 96 corresponding to each of the chucks located at the loading stations does not rotate during the indexing period of the turret, so that the clutches 94-95 may be engaged readily, but immediately after the indexing period and after chuck clutches 94-95 are engaged, cam 117 on cam disc 46 engages clutch 113 so that the chucks 90 rotate.

At the end of the forward movement of the tools, cam drum 165 lies in the relative position illustrated in Figure 13, with left-hand mutilated gear 171 beginning to reverse the movement of cam drum 165 to retract the tools after they have performed their several tooling operations on the corresponding pieces of work. Movement of the cam drum into the relative position illustrated in Figure 12 results in the retraction of the tools from the work and also the elevation of the work locators 225 and 226 and their gauges from the pieces of work previously placed in the open chucks at the loading station preparatory to the next indexing movement of the turret, which is performed by the same mechanism in the manner just described.

If it is desired to adjust the tool slides for the purpose of taking test measurements of the work, the operator can reverse or back up the tools, when the tool slides are in the proper position, 5 by moving handle bars 75 or 78 to the left to disengage main driving clutch 53 and engage reversing clutch 65 (Fig. 4). When reversing clutch 65 is engaged the rotation of drive shaft 54 is reversed through idler gear 68, which is interposed between driving pinion 69 on shaft 35 and the spur gear 67 carried by the reversing clutch 65. This arrangement enables checking of the tools at any time.

If the operator fails to remove a finished piece 15 of work after the tooling cycle has been completed, the machine is automatically stopped to prevent unnecessary operations as well as the re-tooling of the finished piece of work. The safety mechanism devised for this purpose and illustrated especially in Figures 14 to 17 inclusive, 20 assumes the position illustrated in Figure 17, so that plunger 241 is depressed into alignment with the lug 245 on the lever 74 of control handle bar 75, so that during the subsequent feeling action 25 of cam 236, plunger 241 is projected to the left to actuate the control bar 75 and disengage main driving clutch 53. This arrangement enables one operator to attend to a number of machines with safety, for if he does not return to a machine in time it is automatically stopped in the 30 manner described.

Also, if the operator holds treadle 210 depressed longer than the indexing mechanism of the turret allows, the safety mechanism assumes 35 the position illustrated in Figure 16, so that, during the subsequent feeling action of cam 236, the safety mechanism actuates control bar 75 to disengage main driving clutch 53 to stop the machine. The same operating conditions take place 40 in the event that the work is not properly seated in the chucks, as detected by the work locators 225 and 226 or their corresponding gauges. This renders the entire machine substantially fool-proof and accident-proof, insuring that the work 45 is properly handled under all conditions of operation.

By the arrangement of the tool lubricant discharge trough 262 and the cooperating downward slope of the upper surface of the turret 89, 50 the chips are flushed clear of the machine out of the spout 263 without the necessity of using mechanical chip scrapers or flushing devices.

Among the numerous novel features of the machine especial importance is attached to the 55 mounting and correlation of the several tools which perform their individual tooling operations on the succeeding pieces of work presented to them by the indexing movements of the turret. For example, the oscillating cam drum 165 carries 60 a series of cam segments 164 which are individual to the corresponding tools and actuate the tools in accordance with their tooling requirements. Thus, by changing the cam segments the corresponding individual tools actuated thereby may 65 be provided with various movements.

The horizontal or cross tool slides are also controlled by individual cams mounted on constantly 70 rotating shafts located within the two side columns of the machine, each of which carries a tool slide on its front and rear surfaces, so that facing work, cross drilling, reaming, or the like, may be performed at four of the six tooling stations.

The chuck spindle driving mechanism is also 75 of importance, being extremely simple and com-

pletely enclosed and effected by means of a shaft 103 within the vertical center column of the machine which transfers the drive from the top of the machine to the individual driving gears of the several chucks. Also, by properly adjusting the 5 drive of the chucks by means of shiftable gears 111, all of the chucks may be rotated at a selected speed while, by adjusting and arranging the driving gears 98 and 99 of the individual chucks, each 10 piece of work is driven at a speed commensurate with its nature and the kind of tooling which is to be performed thereon.

Also, by means of a single cam operating upon the vertical push rod 126 extending through the center column, both the rotation of the chucks located at the tooling stations and the opening of the chucks located at the loading station are controlled concurrently. The arrangement simplifies the construction and operation of the machine and provides a convenient means whereby 20 steps incidental to the main tooling operation are performed without interference with the tooling operations.

The indexing mechanism whereby the movements of the massive work-holding turret are controlled 25 as easily as a turret of much less mass rotating at much less speed, is of special importance, and these advantages are in part due to the converging and diverging abutments, which are engaged alternately by the indexing mechanism, so that the 30 massive turret is set into motion slowly and easily and its inertia overcome with a gradual movement, while the stopping of the turret at the end of the indexing movement is performed as slowly and as easily while overcoming the momentum of its movement without shock or strain on the moving parts.

I claim:

1. In a machine of the class described, the combination of a support, a plurality of rotatable 40 work holders on the support, means for opening the work holders but normally disconnected therefrom, means for rotating the work holders but normally disconnected therefrom and an element common to both of said means and having direct connections therewith, said element being movable to actuate said means toward the work 45 holders.

2. In a machine of the class described, the combination of a work holding member having a plurality of rotary work holders, a tool holding member having a plurality of tools, mechanism for relatively moving the members intermittently to place successive tools and pieces of work in co-operative relation, means for opening successive 55 work holders, means for rotating other work holders, and a common element connected to both of said means, said element being movable reciprocally to render both of said means ineffective during relative movements of the members and to 60 render both of said means effective between the relative movements of the members.

3. In a machine of the class described, the combination of a turret, a plurality of rotatable work holders arranged thereon in circular series, 65 tools arranged for operation on successive pieces of work in the work holders, mechanism for indexing the turret to present successive pieces of work to the tools, means for opening the work holders, means for rotating the work holders, and 70 a movable element common to both of said means and having direct connections therewith, whereby one movement of said element disables both of said means substantially simultaneously during each indexing movement of the turret.

4. In a machine of the class described, the combination of a turret, a plurality of rotatable work holders arranged thereon in circular series, tools arranged for operation on successive pieces of work in the work holders, mechanism for indexing the turret to present successive pieces of work to the tools, means for opening at least one of the work holders, means for rotating other work holders, and a common element connected to both of said means, said element being movable reciprocally to disable both of said means during indexing movements of the turret and to render both of said means effective during dwell periods of the turret. 5
5. In a machine of the class described, the combination of a turret, a plurality of rotatable work holders arranged thereon in circular series, tools arranged for operation on successive pieces of work in the work holders, mechanism for indexing the turret to present successive pieces of work to the tools, means for opening at least one of the work holders but disengaged therefrom during indexing periods of the turret, means for rotating other work holders but disengaged therefrom during indexing movements of the turret, and a rod connected to both of said means, said rod being movable axially to actuate said means toward and away from the work holders during dwell periods of the turret. 10
6. In a machine of the class described, the combination of a turret, a plurality of rotatable work holders arranged thereon in circular series, tools arranged for operation on successive pieces of work in the work holders, mechanism for indexing the turret to present successive pieces of work to the tools, means for opening at least one of the work holders and being in engagement therewith during dwell periods of the turret, means for rotating other work holders and being in engagement therewith during dwell periods of the turret, common mechanism for substantially simultaneously disengaging both of said means during indexing periods of the turret to close said one work holder and stop the rotation of said other work holders, and a single cam for actuating said mechanism. 15
7. In a machine of the class described, the combination of a turret, a plurality of rotatable work holders arranged thereon in circular series, tools arranged for operation on successive pieces of work in the work holders, mechanism for indexing the turret to present successive pieces of work to the tools, means for opening at least one of the work holders, means for rotating other work holders, common mechanism for substantially simultaneously disabling both of said means during indexing movements of the turret and for rendering both of said means effective during dwell periods of the turret to open said one work holder and rotate said other work holders, and a single cam for actuating said mechanism. 20
8. In a machine of the class described, the combination of a frame having a center column, a turret journaled on said column, a plurality of rotatable work holders arranged thereon in circular series, tools arranged for operation on successive pieces of work in the work holders, mechanism for indexing the turret to present successive pieces of work to the tools, means for opening at least one of the work holders, means for rotating other work holders, separable connecting devices between each of said means and the corresponding work holders, and common mechanism controlling the devices for substantially simultaneously rendering the means effective during dwell periods of the turret and ineffective during indexing periods of the turret, said mechanism including an actuating rod connected at one end with both of said means and extending through said column. 25
9. In a machine of the class described, the combination of a frame, a turret journaled on the frame and having a plurality of work holders, a plurality of tool holders on the frame, intermittently oscillating means on the frame for moving the tool holders to place their tools into and out of cooperative relation with the work in the turret work holders, and mechanism for alternately engaging and disengaging said means for oscillating the same. 30
10. In a machine of the class described, the combination of frame, a turret journaled on the frame and having a plurality of work holders, a plurality of tool holders on the frame, oscillating means on the frame for moving the tool holders to place their tools into and out of cooperative relation with the work in the turret work holders, and intermittent gearing periodically engaging the means for oscillating the same. 35
11. In a machine of the class described, the combination of frame, a turret journaled on the frame and having a plurality of work holders, a plurality of tool holders on the frame, oscillating means on the frame for moving the tool holders to place their tools into and out of cooperative relation with the work in the turret work holders, said means including a cam ring having segments individual to the several tool holders, and mechanism periodically engaging the ring for oscillating the same. 40
12. In a machine of the class described, the combination of frame, a turret journaled on the frame and having a plurality of work holders, a plurality of tool holders on the frame, oscillating means on the frame for moving the tool holders to place their tools into and out of cooperative relation with the work in the turret work holders, said means including a carrier having cams individual to the tool holders, and devices intermittently engaging said mechanism for oscillating the carrier. 45
13. In a machine of the class described, the combination of frame, a turret journaled on the frame and having a plurality of work holders, a plurality of tool holders on the frame, oscillating means on the frame for moving the tool holders to place their tools into and out of cooperative relation with the work in the turret work holders, said means including a carrier having cams individual to the tool holders, a device for moving the carrier in one direction, and a second device for moving the carrier in the opposite direction, said devices alternating in their engagement with the carrier to oscillate the same. 50
14. In a machine of the class described, the combination of frame, a turret journaled on the frame and having a plurality of work holders, a plurality of tool holders on the frame, oscillating means on the frame for moving the tool holders to place their tools into and out of cooperative relation with the work in the turret work holders, said means including a carrier having cams individual to the tool holders, gear segments on the carrier, and mutilated gears alternately engaging the corresponding gear segments to oscillate the carrier. 55
15. In a machine of the class described, the combination of a frame, a turret journaled on the frame and having a plurality of work hold- 60
- 70
- 75

ers, a plurality of columns on the frame extending above the turret and substantially parallel to the axis of the turret, and tool holders mounted upon substantially opposite sides of the columns above the turret and movable to place their tools into and out of cooperative relation with the work in corresponding turret work holders.

16. In a machine of the class described, the combination of a frame, a turret journaled on the frame and having a plurality of work holders, a plurality of columns on the frame extending above the turret and substantially parallel to the axis of the turret, tool holders mounted upon substantially opposite sides of the columns above the turret and movable to place their tools into and out of cooperative relation with the work in corresponding turret work holders, and means in the columns for actuating the corresponding tool holders.

17. In a machine of the class described, the combination of a frame, a turret journaled on the frame and having a plurality of work holders, a plurality of columns on the frame extending above the turret and substantially parallel to the axis of the turret, tool holders mounted upon substantially opposite sides of the columns above the turret and movable to place their tools into and out of cooperative relation with the work in corresponding turret work holders, and means on the columns individual to the several tool holders thereon for actuating the latter.

18. In a machine of the class described, the combination of a frame, a turret journaled on the frame and having a plurality of work holders, a plurality of columns on the frame extending above the turret and substantially parallel to the axis of the turret, tool holders mounted upon substantially opposite sides of the columns above the turret and movable to place their tools into and out of cooperative relation with the work in corresponding turret work holders, and a plurality of cams within each column corresponding to the several tool holders thereon for actuating the latter.

19. In a machine of the class described, the combination of a frame, a turret journaled on the frame and having a plurality of work holders, a plurality of columns on the frame extending above the turret and substantially parallel to the axis of the turret, tool holders mounted upon substantially opposite sides of the columns above the turret and movable to place their tools into and out of cooperative relation with the work in corresponding turret work holders, a shaft within each column, and connections between each shaft and the corresponding tool holders for actuating the latter.

20. In a machine of the class described, the combination of a frame, a turret journaled on the frame and having a plurality of work holders, a plurality of columns on the frame extending above the turret and substantially parallel to the axis of the turret, tool holders mounted upon substantially opposite sides of the columns above the turret and movable to place their tools into and out of cooperative relation with the work in corresponding turret work holders, a rotary shaft within each column, and a plurality of cams on each shaft individual to the several corresponding tool holders for actuating the latter.

21. In a machine of the class described, the combination of a frame, a turret journaled on the frame and having a plurality of work holders, longitudinal tool holders on the frame movable to place their tools into and out of cooperative

relation with the work in the turret work holders, a plurality of columns on the frame extending substantially parallel to the axis of the turret, and a plurality of transverse tool holders on each column movable to place their tools into and out of cooperative relation with the work in the turret work holders, and means for concurrently actuating the longitudinal and transverse tool holders.

22. In a machine of the class described, the combination of a frame, a turret journaled thereon and having a plurality of work holders, a plurality of tool holders on the frame and movable substantially longitudinally of the frame for placing their tools into and out of cooperative relation with the work in the turret work holders, a plurality of rotary shafts extending substantially parallel to the axis of the turret, transverse tool holders actuated by the shafts for placing the tools carried by the tool holders into and out of cooperative relation with the work in the turret work holders, and mechanism actuated by the rotary shafts for actuating the longitudinal tool holders.

23. In a machine of the class described, the combination of a frame, a turret journaled thereon and having a plurality of work holders, a plurality of tool holders on the frame and movable substantially longitudinally of the frame for placing their tools into and out of cooperative relation with the work in the turret work holders, a plurality of rotary shafts extending substantially parallel to the axis of the turret, transverse tool holders actuated by the shafts for placing the tools carried by the tool holders into and out of cooperative relation with the work in the turret work holders, oscillating mechanism for actuating the longitudinal tool holders, and connections between the rotary shafts and the mechanism for oscillating the latter.

24. In a machine of the class described, the combination of a frame, a turret journaled thereon and having a plurality of work holders, a plurality of tool holders on the frame and movable substantially longitudinally of the frame for placing their tools into and out of cooperative relation with the work in the turret work holders, a plurality of rotary shafts extending substantially parallel to the axis of the turret, transverse tool holders actuated by the shafts for placing the tools carried by the tool holders into and out of cooperative relation with the work in the turret work holders, oscillating mechanism for actuating the longitudinal tool holders, and means on the individual rotary shafts periodically engaging the mechanism to oscillate the latter.

25. In a machine of the class described, the combination of a frame, a turret journaled thereon and having a plurality of work holders, a plurality of tool holders on the frame and movable substantially longitudinally thereof for placing their tools into and out of cooperative relation with the work in the turret work holders, individual cams for the several tool holders, a carrier for the cams, a plurality of columns on the frame extending substantially parallel to the axis of the turret, a plurality of tool holders on each column and movable substantially transversely thereof for placing their tools into and out of cooperative relation with the work in the turret work holders, a rotary shaft in each column, cams on each shaft individual to the corresponding transverse tool holders for actuating the latter, and intermittently operative connections between at least one of the shafts and the carrier for oscillating the latter.

26. In a machine of the class described, the combination of a frame having a center column, a turret journaled thereon and having a plurality of rotary work holders, a rotary drive shaft extending through the column, driving connections between the shaft and the work holders, and means for controlling the connections extending through the column.
27. In a machine of the class described, the combination of a frame having a center column, a turret journaled thereon and having a plurality of rotary work holders, a rotary drive shaft extending through the column, driving connections between the shaft and the work holders, and clutches individual to the work holders in the said driving connections.
28. In a machine of the class described, the combination of a frame having a center column, a turret journaled thereon and having a plurality of rotary work holders, a rotary drive shaft extending through the column, driving connections between the shaft and the work holders, clutches individual to the work holders in the said driving connections, and means extending through the column for actuating the clutches.
29. In a machine of the class described, the combination of a frame having a center column, a turret journaled thereon and having a plurality of rotary work holders, a rotary drive shaft extending through the column, driving connections between the shaft and the work holders, and speed change mechanism for varying the speed of rotation of the shaft.
30. In a machine of the class described, the combination of a turret, an abutment on the turret sloping in the direction of movement of the turret, and a moving pawl engaging the abutment to index the turret, the slope of the abutment causing the pawl to retard the initial movement of the turret.
31. In a machine of the class described, the combination of a turret, an abutment on the turret sloping in the direction of movement of the turret, a second abutment on the turret sloping in a direction opposite to the slope of the first abutment, and a pair of moving pawls successively engaging the two abutments to index the turret, the slope of the first abutment causing the first pawl to retard the initial movement of the turret and the slope of the second abutment causing the second pawl to retard the final movement of the turret.
32. In a machine of the class described, the combination of a turret, work holders on the turret, tools for operating on the work in the work holders, and a trough surrounding the turret substantially below the level of the work holders and having a continuous downward slope toward a discharge point, the upper surface of the turret sloping steeply downwardly to the trough, whereby the chips removed from the work by the tools are flushed into and down the trough in a continuous stream to said discharge point by the usual tool lubricant during the tooling operations.
33. In a machine of the class described, the combination of a turret, work holders on the turret, tools for operating on successive pieces of work in the work holders, certain of said tools performing roughing operations on the work, and a trough surrounding the turret below the level of the work holders and having a discharge point adjacent the stations of the roughing tools, said trough sloping downwardly toward the discharge point for causing the usual tool lubricant to flush the chips in a continuous stream into and down the trough and toward the discharge point thereof during the tooling operations.
34. In a machine of the class described, the combination of a frame, a turret journaled on the frame and having a plurality of work holders, a plurality of tool holders on the frame, oscillating means on the frame for moving the tool holders to place their tools into and out of cooperative relation with the work in the turret work holders, mechanism for periodically engaging said means for oscillating it, and other mechanism for periodically engaging said means for holding it in a fixed position during the stationary periods thereof.

ARTHUR J. LEWIS. 45
